DOOR CHECK AND THE LIKE

James G. Knipe, Princeton, N. J.

Application August 8, 1950, Serial No. 178,310

20 Claims. (Cl. 16—66)

1

This invention relates to door checks and the like; and it consists of a device suitable for use as a door check or the like comprising an assembly of telescoping rigid tubes closed off at the ends by end plates forming air tight seals, a concentric resilient tube mounted outside the rigid tubes, said resilient tube covering the joints between said telescoping rigid tubes, whereby the assembly as a whole forms a bellows, and venting means permitting the passage of a minute flow of air into and out of said bellows; said resilient tube being mounted so that, when the assembly of rigid tubes is extended upon opening of the door, the resilient tube hugs the rigid tube assembly, whereby a delay is caused before the door starts to close; all as more fully hereinafter set forth and as claimed.

Objects of the present invention are to improve and simplify present door devices, to lessen the cost of present door checking devices and to simplify the construction of same, and specifically to provide in one device means for holding a door open and stationary for an adjustable period of time, for automatically closing said door at the end of such time and for causing the door to shut quickly but quietly.

Other objects of the present invention are to provide a unit which may be easily and cheaply attached to doors in offices, libraries, homes, hospitals and other institutions for the convenience and safety of the personnel afforded by the device, to provide a device which will prevent injuries and falls due to hitting or being tripped by a closing door, to provide by this device a means to hold a door open and stationary so a person with both arms occupied or filled may by bodily contact, as by pushing with a foot, open the door and pass through without having said door swing back and hit him or in any way affect him, and to have a unit which is sufficiently cheap to enable use on numerous doors of institutions.

A large number of different types of door checks have been developed and put to use. Some of these merely prevent the door from slamming when it closes while others close the door both slowly and positively. But in the case of many doors, such as those in restaurants, railway stations and hospitals it would be advantageous if, after opening, they would remain in open position for a relatively short period before they start to close. To my knowledge no simple and practical door check has been developed heretofore which is capable of producing this desired delaying effect followed by automatic closing of the door.

2

I have discovered that it is possible to produce a delay of the type described by a door check which makes practical use of the fact that, when a resilient tube is stretched, its diameter becomes reduced so that it will grip or hug a concentric inner tube over which it fits closely, but not tightly, when in unstretched condition. This hugging action continues for a short period even after tension on the resilient tube has been relaxed. The hugging action can be increased, prolonged and/or controlled in its time period by the use of a vacuum inside the resilient tube. For example, I have discovered that the hugging action will continue after tension on the resilient tube has relaxed as long as a vacuum is maintained inside the tube assembly. If a controlled air leak is provided which will permit a minute flow of air into the assembly an accurate control on the time period of the hugging is obtained.

20 I make practical use of these phenomena in my door check which comprises an assembly of rigid telescoping tubes closed off air tight at their outer ends and an outer resilient tube extending over the joints between the rigid tubes and secured thereto by air tight joints in such fashion that the assembly of tubes as a whole forms in effect a bellows in which a partial vacuum can be produced by extending the device and a pressure by compressing it. A small controlled leakage of air into and out of the bellows is advantageous and this can be accomplished by having an air vent and means for controlling the flow of air through the vent.

35 The desired gripping or hugging action which produces the desired delay before the door starts to close may be effected (1) by the stretching of the resilient tube alone, (2) by the vacuum produced inside the assembly of tubes or (3) by a combination of the stretching effect and the vacuum effect. If stretching of the resilient tube is relied upon to produce the hugging effect it is essential, of course, for this tube to be secured to the rigid tubes by tight joints so the resilient tube will be stretched when the assembly of tubes is extended. When the resilient tube is thus stretched it tends to pull the assembly back into its compressed position and hence it is usually not necessary in the case of this embodiment to employ a separate spring to close the door.

40 50 55 If one end of the resilient tube is attached to the rigid tube beneath it by means of a sliding joint, it is necessary to rely upon the vacuum produced inside the tube assembly in order to obtain the required hugging action. This vacuum tends to close the door, but a slight leakage of air into the assembly is necessary in order

to release the grip of the resilient tube upon the rigid tube beneath and, as the door is closed and the assembly simultaneously compressed, a slight air pressure builds up inside the assembly. This necessitates the use of a spring to effect complete closing. The spring may be mounted inside the tube assembly or a conventional spiral screen door spring can be used if desired as an auxiliary element.

It is preferable to use the combined effect of a vacuum and the stretching of the resilient tube to produce the described gripping or hugging effect since, if this is done the length of the delay prior to closure of the door can be closely controlled by control of the quantity of air passing through the air vent. When both effects are utilized it is necessary, of course, to secure the ends of the resilient tube tightly to the rigid tubes beneath, so the resilient tube is stretched, and also to employ means for regulating the quantity of air admitted through the air vent.

The resilient tube used on my door check can be a straight rubber tube in the cheaper embodiments but it is more advantageous to employ an accordion plaited tube. This reduces the friction in the device. Both types of resilient tubes can be tapered if desired so their ends fit the rigid tubes closely. To make tight joints between the resilient tube and the rigid tubes, any suitable plastic rubber cement can be used, which is capable of forming a tight joint between metal and rubber. If desired it is possible, of course, to rivet the ends of the resilient tube to the rigid metal tubes in which case the cement used has the primary purpose of making the joint air tight.

My invention can be explained in greater detail by reference to the accompanying drawings which show, more or less diagrammatically, four embodiments of my door check. In this showing, Fig. 1 is an elevation of my bellows type door check.

Fig. 2 is an end view of the bellows type check, taken from the left hand end of Fig. 1.

Fig. 3 is a longitudinal section of the same device, taken along the line 3—3 of Fig. 2 and shown in compressed position.

Fig. 4 is a similar view of the bellows type check in extended position.

Fig. 5 is a longitudinal section through a modified door check.

Fig. 6 is a longitudinal section through a second modification.

Fig. 7 is a similar view through a third modification, while

Fig. 8 is a perspective view of a bellows type check secured between the top of a door frame and the plate at the top of the door.

In the various views like parts are designated by like reference numerals. The bellows type door check shown in Figs. 1, 2, 3, 4 and 8 is formed with a rectangular base plate 1 to which a base or outer tube 2 is welded or otherwise secured so that the plate closes the end of the tube with an air tight joint. A smaller inner tube 3 telescopes into tube 2 with a loose sliding fit and the outer end of this smaller tube is closed by means of a rectangular end plate 4 with an air tight joint. An elastic tube 5 which is preferably accordion plaited and tapered slightly extends between the two tubes, being secured air tight by a cement, for example, at 6 to the inner end of the base tube and at 7 to the remote end of the inner tube. The two telescoping tubes 2 and 3, with the end plates 1 and 4, and the elastic tube 5 form in effect a bellows which can be com-

pressed into the positions shown in Figs. 1 and 3 or expanded into the position shown in Fig. 4. A vent hole 8 is provided to provide a flow of air into and out of the bellows.

In my preferred embodiment, shown in Figs. 1, 2, 3, 4 and 8, means are provided for controlling the quantity of air passing through the vent hole, this means taking the form of a rubber or other plastic elastic tube 9 which is slipped over the base tube 2 and usually folded over at one end as at 10. By folding this tube over to a greater or lesser extent the amount of air passing through the vent can be closely controlled.

For proper operation of my door check it is essential to have a minute leakage of air through vent 8 in order gradually to break the vacuum when the check is extended as shown in Fig. 4. For this reason it is advantageous to employ a material which is slightly porous as well as elastic for the sleeve 9, such as foam rubber, for example. As the door closes any excess air in the bellows can readily escape through the vent 8.

The end plates 1 and 4 can be used conveniently as means for securing my door check to the door and the door framework. As shown in Figs. 1, 2, 3, 4 and 8 these plates can be provided with extensions 11 provided with holes 12 for mounting purposes. A convenient way of mounting this type of door check is shown in Fig. 8. This figure is a perspective view representing the top of a door 13, hinged at the left to the door jamb 14 upon hinges 15 in such manner that the door opens outwardly. A door check of the bellows type is secured at its base end to the plate 16 at the top of the door by means of a staple 17 which passes through the hole 12 in the end plate 1. At its other end the door check is secured in similar manner to the door frame by staple 18 which passes through the hole 12 in end plate 4. The staple 18 is conveniently positioned about 2 inches inwardly from the door jamb and approximately 1½ to 2 inches below the door plate. The position of staple 17 depends, of course, upon the length of the door check but it can be conveniently placed about 1 to 2 inches inwardly from the door when the latter is in its closed position. This mounting is not conventional but is advantageous for my door check owing to the fact that the check is extended only from about 1½ to 2 inches when the door moves from its closed position to its 90° open position, these figures applying to a check having an over-all length of about 9 inches and having a 5 inch bellows, whose outer metal tube has a diameter of about 1¼ inches and whose inner metal tube has a diameter of about 1½ inches.

When a door check is mounted in conventional fashion the extension required usually amounts to from about 5 to 7 inches. An extension of this magnitude requires a bellows having a length of approximately 8 inches or longer and, since the elastic bellows of my door check is the most expensive element in the device it is advantageous to keep this as short as possible.

As already mentioned it is possible to make use of the reduction in diameter alone to effect a delayed closing of a door equipped with one of my door checks. Modifications making use of this single effect are shown in Figs. 5 and 6. In the modification of Fig. 5 a straight rubber tube 5a is used in place of the accordion plaited tube of the preferred modification. And the vent 8 may be left open. The telescoping tubes 2a and 3a may be made of considerably smaller diameter, if desired, the inner tube being from about ½ to

1 inch in outer diameter and the outer tube slightly larger to fit. In this modification the tubes 2a and 3a are closed off at their ends by means of butt hinges, shown generally at 19, having plates 1a, 11a and 4a, 11a, respectively, mounted on hinge pins 20. Tube 2a is welded or soldered to the hinge plate 1a with an air tight joint while tube 3a is secured in similar manner to hinge plate 4a. The free hinge plates 11a at either end are provided with screw holes 12a used in mounting the device. Rubber tube 5a is secured to tube 2a by an air tight joint 6 as in the modification of Fig. 1.

The modification of Fig. 5 can be mounted in conventional manner between the door jamb and the door frame by screws secured therein and passing through screw holes 12a. When a door equipped with the modification of Fig. 5 is opened, the tube 5a stretches and is thereby caused tightly to hug the tube 3a. Air is drawn into the vent 8 so that the vacuum produced in the bellows is negligible unless the door is opened very quickly. However the friction of the tube 5a against the tube 3a is sufficient to cause a delay in the closing of the door. Air escapes from the vent 8 during closing but the vent is sufficiently small so that slamming of the door is prevented.

A further modification of my door check is shown in Fig. 6. In this modification the tube 2b can be made identical to the tube 2 of the modification shown in Figs. 1, 2, 3, 5 and 7. But the tube 3b is of the same size as 2b and is advantageously of about the same length. The smaller tube 21 fits inside tubes 2b and 3b with a loose fit and may be sufficiently long to hold the rubber tube 5b slightly stretched even when the check is in its compressed position, at which time its ends bear against the plates 1 and 4. In this modification the rubber tube 5 may be either accordion plaited or smooth, a smooth tube being shown in Fig. 6. This tube is secured by air tight joints 6 and 7 to tubes 2b and 3b, respectively, preferably by a cement. A spring 22 can be mounted inside tube 21, as shown, being fastened at its ends to end plates 1 and 4. If desired a similar spring may be used in the other modifications of my door check. It serves to supplement the action of the rubber tube in making the door close tightly. Such a spring serves as a safety factor since, if the joint at 7 should become loose for any reason, the check will still operate satisfactorily owing to the action of the spring serving to close the door; otherwise the check would be inoperative in closing the door.

When a sliding fit is used at one end of the flexible tube it is necessary to employ a spring to effect complete closing of the door. A modification of this type is shown in Fig. 7. This modification is exactly like that of Figs. 1, 2, 3, 4 and 8, except that the joint 1a at the left end of the accordion plaited tube 5c is a sliding joint which should fit closely but need not be air tight and that a spring 22 is provided to close the door. In the operation of this modification, when the door is opened a vacuum is produced inside the tube assembly. The resilient tube 5c is not stretched, in fact the length of this tube may be decreased slightly due to the effect of the vacuum tending to reduce its length. But the vacuum causes the tube 5c to grip or hug the tube 3 which produces the desired delay before the door starts to close. The vacuum also causes the sliding joint at 1a to become substantially air tight. When the vacuum has been gradually dissipated by the slow leakage of air through the vent 8 and

under the sleeve 9, the gripping action stops and the spring 22 closes the door. The air which has leaked into the tube assembly becomes compressed and this prevents slamming of the door. But this air escapes rather quickly since it raises the sleeve 10 which acts somewhat like a one-way valve. Hence the door closes rather quickly and slightly after the delay mentioned. In this as well as in the modification of Figs. 1, 2, 3, 4 and 8 the delay produced prior to the closing of the door can be controlled by regulating the size of the vent 8 and the extent to which it is closed by the tube 9. This delay can also be controlled conveniently by the person who opens the door since the further the door is opened the longer the delay produced before it starts to close. This is a unique and inherent feature of my door check.

In order to insure complete closing of a door to which one of my devices is attached in which no auxiliary spring is employed, the resilient tube 5 should be under a slight tension even when the device is in its compressed position. This tube should be sufficiently rigid so that it does not buckle when the door is closed yet sufficiently elastic to stretch at least from about 1½ to 2 inches when the door is opened. My tests show that a vulcanized natural rubber tube having a thickness of from about $\frac{1}{32}$ to $\frac{1}{16}$ inch has the proper characteristics.

In one operating embodiment, of the type shown in Figs. 1, 2 and 3, the tube is 5 inches long, having an inner diameter of 1½ inch, with 16 accordion plaiting and the thickness of the rubber is $\frac{1}{16}$ inch at the ends, where it is secured to the metal tubes and $\frac{1}{16}$ inch in between. This tube stretches from about 2 to 3 inches as the door is opened. This tube is sealed at one end to the inner end of an aluminum tube having a length of 5 inches, an outer diameter of 1¼ inches and a wall thickness of .058 inch, while the other end of the resilient tube is sealed close to the outer end of a smaller aluminum tube which telescopes the larger tube, said smaller tube having a length of 11 inches, an outer diameter of 1½ inches and a wall thickness of .046 inch. The clearance between two telescoping tubes of this type is advantageously from about 0.009 to 0.027 inch. It can be greater but preferably not over 0.060 inch. The air vent can be made with a diameter of from about $\frac{1}{64}$ to $\frac{1}{32}$ inch. If uncovered it should be from about $\frac{1}{64}$ to $\frac{1}{32}$ inch in diameter depending upon the cubic volume of the door check.

In the specific device described above the air vent was $\frac{1}{32}$ inch in diameter and was covered by a rubber sleeve which substantially prevented the access of air during opening of the door. This device caused the door to hold its open position for a period varying from about 5 to 15 seconds before it started to close, depending upon the extent to which the door was originally opened. With the vent entirely uncovered the delay was reduced to about half of these figures.

While I have disclosed what I consider to be the best modifications of my door check it is evident, of course, that various modifications can be made in the specific structures which have been described without departing from the purview of this invention. While I have described the rubber tube 5 as being slightly tapered, it is possible, if the tube 2 is sufficiently thin and if tube 3 makes a close sliding fit with this tube, to employ a straight rubber tube. The tube 5 is sufficiently resilient so that it can readily be

clamped air tight at 1. If tube 5 is molded specially, the end which is secured to tube 3 can be made to fit this tube while the other end can be made slightly larger to fit the tube 2, the tube between these ends being made without a taper. The tube 5 obviously can be made of any elastic plastic material which is substantially impervious. Natural rubber or any of the synthetic elastomers can be used, for example. It is advantageous to employ an elastomer which is resistant towards oil, such as neoprene, since customers are likely to put oil in the vent hole 8 thinking that my check operates similar to conventional door checks which operate with a plunger. There is a slight tendency for the tube 5 to stick to the metal tube 3 when the check is in its expanded position. This tendency can be overcome by dusting the tube 3 or the inside of tube 5 with graphite or talc, for example. A single application of one of these materials is usually sufficient to last indefinitely if the rubber tube is properly made.

While I have described my device as being used primarily for a door check it is evident that it can be made use of for any purpose in which it is desired to produce a buffering or dash-pot effect while permitting a motion in one direction for a short distance followed by a delay and then a return motion with a buffering effect. Thus my device can be used as a dash pot or as a recoil mechanism for a gun or the like.

The tubes used in my device are not necessarily cylindrical; a square or rectangular section can be used if desired. Cylindrical tubes are generally cheaper and hence preferred for most purposes. My device can be made of any size desired according to the use to which it is put. The rigid tubes can be made of metal, such as aluminum or steel, and it is also possible to make these of any of the conventional molded plastics, such as phenol-formaldehyde resins, polymerized vinyl resins, etc. The air vent used in my device may be positioned at any convenient point on the tube assembly and, of course, any conventional means can be used for controlling the rate of air flow therethrough. Further modifications of my device which fall within the scope of the following claims will be immediately evident to those skilled in the art.

What I claim is:

1. A device suitable for use as a door check to be mounted between a door and its framework, comprising an assembly of telescoping rigid tubes closed off at their outer ends by plates forming air tight seals, a closely fitting concentric resilient tube mounted with substantially air tight joints outside the rigid tubes, said resilient tube covering the joints between said telescoping rigid tubes, whereby the assembly as a whole is substantially air tight and at least a partial vacuum is produced inside the assembly when it becomes extended as the door is opened, said vacuum causing said resilient tube temporarily to hug the rigid tubes whereby a delay is caused before the door starts to close, and resilient means tending to pull the said assembly together to close the door.

2. The device of claim 1 wherein said resilient tube is tightly secured to two of said rigid tubes whereby it is stretched as the door is opened, said resilient tube comprising the resilient means tending to close the door.

3. The device of claim 1 wherein said resilient tube is tightly secured to one of said rigid tubes and has a sliding fit with another, a spring being

50
55

provided to pull the assembly of tubes together to close the door.

4. The device of claim 1 wherein said resilient tube is accordion plaited.

5. The device of claim 1 wherein said resilient tube is tapered in order to fit the tube assembly closely.

6. The device of claim 1 wherein said resilient tube is a straight rubber tube.

7. The device of claim 1 wherein the assembly of rigid tubes consists of two end tubes of the same size closed off at their outer ends and a longer concentric inner tube, the resilient tube being mounted outside the inner tube and tightly secured to the inner ends of said end tubes.

8. The device of claim 1 wherein the assembly of rigid tubes consists of two concentric tubes the inner tube being longer than the outer tube, the said resilient tube being rigidly connected to the inner end of the outer tube and to the inner tube close to its end plate.

9. The device of claim 1 wherein the assembly of rigid tubes consists of two tubes the inner tube being longer than the outer tube, the said resilient tube being rigidly secured to the inner end of the outer tube and having a sliding, substantially air tight fit on the inner tube.

10. The device of claim 1 wherein said end plates are provided with extensions for mounting the check.

11. A device suitable for use as a door check to be mounted between a door and its framework, which comprises a pair of end plates adapted to be used in the mounting of the door check, a pair of telescoping rigid tubes mounted between said end plates and secured thereto with air tight joints, the inner of said tubes being the longer, a closely-fitting accordion-plaited, resilient tube secured with air tight joints at one of its ends to the inner end of the outer rigid tube and at its other end to the inner rigid tube adjacent its end plate, whereby the assembly as a whole forms a bellows, an air vent for controlling the amount of air passing into and out of said bellows, said assembly being so constructed and arranged that, as the assembly is extended upon opening of the door, the resilient tube becomes stretched so that it hugs the said inner tube causing a delay in the closing of the door.

12. The device of claim 11 wherein means are provided to substantially prevent entrance of air through said vent into said bellows as the door is opened whereby the vacuum produced in the bellows assists in causing the resilient tube to hug the rigid tube beneath.

13. The device of claim 11 wherein the air vent is sufficiently large substantially to prevent the production of a vacuum inside the bellows as the door is opened and the resilient tube is caused to hug the rigid tube beneath substantially solely due to its stretched condition.

14. The device of claim 11 wherein said resilient tube is accordion plaited.

15. The device of claim 11 wherein said resilient tube is a straight tube.

16. The device of claim 11 wherein said resilient tube is tapered so that at its larger end it fits the larger rigid tube and at its smaller end it fits the inner rigid tube.

17. A device suitable for use as a door check adapted to be mounted between a door and its framework, which comprises a pair of end plates, a pair of rigid end tubes having the same diameter secured to said end plates with air tight joints, a closely fitting third tube mounted inside and be-

75

tween said end tubes having a length greater than that of said end tubes, a resilient concentric tube tightly secured with air tight joints to the inner ends of said end tubes, the assembly as a whole forming a substantially air tight bellows, means for controlling the amount of air passing into and out of said bellows, the tubes being so constructed and arranged that when the end tubes are pulled apart upon the opening of the door the resilient tube is stretched and caused to hug the inner rigid tube whereby a delay is caused before the door starts to close.

18. A device suitable for use as a door check to be mounted between a door and its framework, which comprises an assembly of telescoping rigid tubes closed off at their outer ends by end plates forming air tight seals, a concentric resilient tube mounted with air tight joints outside the rigid tubes, said resilient tube covering the joints between said telescoping rigid tubes, whereby the assembly as a whole forms a bellows, venting means permitting the passage of a minute flow of air into and out of said bellows, said resilient tube closely fitting the rigid tubes whereby, when the assembly of tubes is extended upon opening of

the door, the resilient tube hugs the rigid tube assembly, whereby a delay is caused before the door starts to close.

19. The device of claim 18 wherein said resilient tube is tightly secured to the rigid tubes so that it is stretched when the door is opened and this tube is thereby caused to hug the rigid tubes.

20. The device of claim 19 wherein said resilient tube is tightly secured at one end to one of the rigid tubes while a sliding joint is provided at its other end so that the vacuum produced upon opening the door causes the tube to hug the rigid tubes.
